EDWARD O. BENJAMIN, OF NEWARK, NEW JERSEY

APPARATUS FOR GENERATING GAS FROM FLUID HYDROCARBONS

Application filed May 3, 1928. Serial No. 274,746.

My present invention is shown as embodied in a complete apparatus or unit adapted for use in the fire boxes of boilers or ordinary furnaces such as are used for heating houses, but it will be found useful in other relations. Some of the basic principles involved are quite similar to those disclosed and claimed in my copending application Ser. No. 264,411, filed March 24, 1928 and 10 Patent No. 1,672,997.

In both cases, the invention resides in a gas producer and a suitable source of heat for operating it. While any suitable source of heat may be employed, the invention, as 15 shown, includes a burner in which fuel oil or other liquid hydrocarbon is burned to produce initial heat, but this heat is utilized to produce a water gas reaction between fluid hydrocarbon and steam, forming carbon 20 monoxide (CO) and hydrogen (H). In normal full operation, however, gas thus produced is preferably the fuel that is employed to keep up the water gas reaction and it is burned under conditions insuring practically complete combustion. As part or all 25 of the gas may be tapped off or all of it may be burned in the burner, the device is obviously adaptable for use in almost any place where generation of heat or of fuel gas 30 is desired.

The object of the invention is to produce complete apparatus of novel construction, especially suited to the above purposes; which may be made of almost any size or 35 capacity; which will stand up under extreme conditions of use or abuse; which will operate efficiently for the production of a completely gasified mixture; which will be automatically self-regulating within very wide 40 limits and which will be practically fool proof in the hands of unskilled users.

The complete combination includes means 45 for generating steam, for supplying water at such a rate as to enable substantially instantaneous or flash vaporization as it passes into the steam generating means, for preventing water from being carried along with the steam, for superheating the steam, for utilizing the steam pressure to atomize and 50 inject fluid hydrocarbon into a reaction

chamber which is maintained at high temperature and wherein the reaction between the hydrocarbon and the steam is effectively promoted, and for burning the gas to produce such steam and to maintain such temperature. The reaction chamber is a passage long enough and having sufficient volume to retard the flow sufficiently to afford time for a complete development of the water gas reaction, but is self-draining so as to avoid trapping 55 or accumulation of liquids. 60

In normal operation, the gasified mixture flows from the reaction chamber through a constricted nozzle under pressure sufficient to produce a powerful injector jet, which 65 discharges into a mixing tube having suitable air draft inlets supplying a substantial amount of primary air to the mixture but not in sufficient quantity to support combustion. The partly aerated gas from the mixing tube flows to a burner beneath the steam generating boiler in heating relation to both 70 said boiler and said reaction chamber, the latter being a coil, preferably in the form of a helix, coaxial with and surrounding a 75 considerable portion of the boiler.

During the preliminary stage prior to normal operation, the hydrocarbon fuel flows through the reaction chamber and the injector jet into a flash pan beneath the boiler. When a sufficient amount of oil accumulates 80 in the flash pan, the oil may be ignited so that the flame will heat up the reaction chamber, steam generator, superheater and other operative elements of the device until steam 85 is generated in sufficient quantity and at pressures necessary to atomize the oil, whereupon the normal water gas reaction begins.

In normal operation, the automatic regulation of the device is due partly to the proportioning of the parts and partly to means for regulating the air draft to the mixing chamber for the burner and to an arrangement to cause relief of the pressure in the steam line in the boiler when a predetermined pressure is exceeded. 90

The primary feature of the regulation referred to results from the fact that with any given rate of oil supply, too great a supply of steam will result in decomposing un- 95

necessarily large amounts of water, producing non-combustible carbon dioxide instead of the desired carbon monoxide. Carbon dioxide so produced operates in two ways; 5 first, it represents a loss of most important fuel constituents; and second, it tends to retard combustion. Moreover, excessive steam is itself a diluent tending to retard combustion. Consequently, generation of steam in 10 excess of what is required for the rate of fuel supply operates immediately to decrease the heat available for generating the steam. On the other hand, the critical temperature and most efficient operation having once been 15 passed, decrease of steam will operate to increase the percentage of combustible carbon monoxide and decrease the steam diluent carrier to intensify combustion, thereby increasing the heat of the flame.

20 In conjunction with such natural self-regulation, due to proportioning of parts, an important feature of my present invention is the provision of a boiler or steam generator comprising a steam chamber of small cross 25 section at its lower end and increasing in cross section toward its upper end, preferably in the general form of an inverted cone, which serves as a flash boiler; and an upper drying or superheating chamber separated from the 30 steam chamber proper by a wall having a restricted orifice therein, means for supplying feed water directly to the lower end of the flash boiler, means for so controlling and restricting the flow of water into the flash 35 boiler that the water so supplied will be evaporated substantially instantaneously.

Another feature is that of providing an outlet near the top of the superheater chamber or steam dome, and leading the steam 40 directly downward from said outlet to an oil injector by means of which the oil is thoroughly atomized and vaporized and combined with the steam is injected into the upper end of a retort. This retort is in the form of a 45 coil, preferably a helix, and arranged to drain from the upper or inlet end to the lower end thereof. The outlet at the upper end of the superheater chamber is also connected with a safety valve which prevents the pressure 50 from becoming excessive and tends to cause a more uniform flow of the steam.

Another feature of the invention consists in the arrangement of the burner with a generally horizontal mixing chamber having at 55 one end a gas nozzle and adjacent air inlets and extends from such ends under the burner outlet and upwardly to communicate with a distributing chamber for the burner outlet and extending in opposite directions in the 60 general form of an arc of a circle. The mixing chamber beneath the burner outlet projects into a flash pan which cooperates therewith to provide a trough around the end of the mixing chamber to receive oil there- 65 from through a passage substantially at the

common level of the floor of the mixing chamber and the flash pan. Preferably, an oil drain is connected with this passage so as to drain both flash pan and mixing chamber. It should be understood that the flash pan is used for burning oil in starting the 70 apparatus.

Another important feature consists in the provision of a burner having a portion with an upwardly facing outlet generally annular in shape and closed by a corresponding shaped deflector of solid cross section and of heat resisting metal. Preferably, this deflector has a downwardly extending tapered flange to divide the current of the gaseous mixture to direct the inner part thereof toward the lower end of the boiler and the other part to a position such that when burned, it will heat the tubular retort more effectively. This deflector is also provided on each side with a series of upward and outwardly extending ribs or vanes which served to control the outward flow of the gaseous mixture and also to support the deflector on the burner proper. Preferably, these vanes are integral with the deflector, but it is obvious that they might be independent thereof, for instance, they might be integral with the outlet structure.

In this structure, the burner outlet is close to the boiler and retort and the mixing chamber is close beneath the burner outlet and supplies the mixture of air and gas at one side of the burner to a distributing chamber extending in both directions around the burner and beneath the outlet, and a feature of the invention consists in providing means for admitting air to flow upwardly inside the ring of the outlet, for example, by providing a passage between the lower wall of the distributing chamber and the upper wall of the mixing chamber at each side of the burner to permit the admission of air to the central part of the burner outlet to facilitate combustion at said outlet.

To enable supply of water to the lower part of the steam chamber of the boiler, a gap is left in the ring of the burner outlet at the side opposite the point where the mixture from the mixing chamber passes into the distributing chamber. Preferably, however, the ends of the mixing chamber and of the deflector, which is an incomplete annulus, are so shaped that together with vanes associated therewith they serve to direct the gaseous mixture across the gap in the annulus to provide a complete circle of combustion.

Another feature of the invention consists in the provision of a rib or fin, preferably integral with the boiler, which extends around the same immediately above the retort except at the side of the boiler from which the steam outlet projects. This rib or fin cooperates with the outlet to control the upward flow of heated gases, thereby ef-

fecting better heating of the boiler, the retort, and the oil injector. It should be noted that the oil injector and the water connection for the boiler are located at the front side of the apparatus.

5 Another feature of the burner arrangement consists in providing a passage communicating at its inner end near the burner with the lower end of the retort coil and 10 extending above the main body of the mixing chamber to the rear side of the gas nozzle which it supplies with gas in normal operation or with oil at other times, as for example, in starting the operation of gas generation. Preferably, a strainer is provided to 15 prevent undesirable material from being carried into the nozzle with the flow of gas. At each side of the nozzle and the passage at the top of the mixing chamber there are vent- 20 tilating openings through which air may be drawn by the action of the gas flowing from the gas nozzle into the mixing chamber. Another feature of the invention relates to means for controlling the admission of air.

25 Another feature relates to the disposal of oil when excessive amounts accumulate in the mixing chamber. The floor of this chamber adjacent to the oil nozzle is somewhat higher than the portion underneath the burner, so that oil flowing out of the gas nozzle, for example, at starting, will flow away from the nozzle and through the communicating passage into the flash pan, where it may be ignited to supply heat for starting the operation. 30 When, however, the oil in the mixing chamber rises above the level of the floor at the oil nozzle, it will flow outwardly past said oil nozzle and be drained from the apparatus in any suitable manner.

40 The above and other features of my invention may be more fully understood from the following description in connection with the accompanying drawings, in which

45 Fig. 1 is a top plan view illustrating one form of my improved apparatus;

Fig. 2 is a front view;

Fig. 3 is a side view from the left of the apparatus shown in Fig. 2;

Fig. 4 is a section on the line 4—4; and

50 Fig. 5 is a fragmentary sectional view along the staggered line 5—5 of Fig. 4.

55 My improved apparatus or unit is very compactly arranged and includes an upper portion in which the steam and gas are generated and a lower portion or burner for heating said upper portion to produce the steam and also to impart sufficient heat to the mixture of steam and atomized or vaporized liquid fuel in a retort portion to raise the mixture to the temperature required to produce the water gas. Preferably, the steam and gas generating device is adapted for use in the fire box of a furnace and may stand on the floor of the fire box, a portion of the burner structure projecting outwardly through

an opening in the lower part of the furnace, such, for example, as that provided by the frame of a door ordinarily used for the removal of ashes.

The gas producer and steam generating portion of the apparatus includes a steam generator or boiler 10 having a lower steam chamber 11 and an upper drying or super-heating chamber 12 separated therefrom by a wall having a restricted orifice and from which steam is supplied to an oil injector 13 which acts to force oil from a supply pipe 14 into the upper end of a self-draining retort 15 including a coil, preferably in the form of a helix, surrounding the boiler 10. In 80 normal operation of the apparatus, the steam chamber 11 serves as a flash boiler, in that water admitted thereto is vaporized substantially instantaneously. In order to produce this effect, the steam chamber 11 is relatively 85 small at the bottom and gradually increases in diameter towards the top, being preferably in the general form of an inverted cone to the lower end of which water is supplied from a supply pipe 16. This pipe is connect- 90 ed with the lower end of a passage or duct, in a vertical tubular member or tube 17, which is threaded into the lower end of the boiler and projects to the upper part of the steam chamber 11. The tubular member 17 has in 95 the sides thereof orifices or openings 18 through which the fluid or water may be projected toward the wall of the steam chamber. The upper end of the tube or tubular mem- 100 ber 17 is closed by a screen 19 which may be of one or more layers of very fine mesh so as to permit passage of fluid air though affording considerable resistance to high velocity flow therethrough. The tubular member 17 and screen 19 constitute a preferred form of 105 a device 20 for screening and throttling upward movement of fluid. This device 20 permits water to collect in the steam chamber 11 when the apparatus is not in operation but restricts such flow so that in full normal op- 110 eration the fluid or water will be vaporized substantially instantaneously upon passing out of said device 20.

The boiler 10 is formed with a horizontal projection in the form of an outlet or duct 115 21 which is close to the boiler with a downward extending internally threaded portion 22 connected by means including the member 23 with a steam chamber 24 of the oil injector 13. At its forward end, the chamber 24 communicates with the rear end of a steam nozzle 25 of which the forward end projects into the entrance of a Venturi tube 26 which connects at its outlet end with the upper 120 end of the tubular retort 15. The forward end of the steam nozzle and the rear end of the Venturi tube provide an annular converging passage through which oil is drawn from a surrounding chamber 27 receiving 125 oil from the pipe 14. The outlet duct 21 is 130

also provided with a branch 28 to communicate with a safety valve (not shown).

Preferably, the heating of the boiler and retort is effected by burning part or all of the water gas generated in the retort. As here shown, the lower end of the retort 15 is threaded into block or member 29 having a passage 30 communicating with the interior of the retort and extending to the lower surface of the block 29 which is substantially a portion of a spherical surface and is therefore adapted to effect a close connection between the passage 30 and the upper end of a passage 31 in a base portion 32 of the apparatus.

A washer 33 is positioned in a suitable annular recess surrounding the upper end of the passage 31 and the block 29 is held firmly against the upper face of the support 32 by suitable means such as screws 34.

From the duct or passage 31, the gas flows outwardly through a duct 35 over the top of a mixing chamber 36 and downwardly through the outer end of the mixing chamber to the bottom or floor thereof, leaving air passages 37 at each side thereof. The inner wall of the vertical portion of the duct 35 is provided with a gas nozzle 38 which directs the gas through the mixing chamber and at the same time draws in air through the inlets. The floor of the mixing chamber 36 is lower in the portion thereof under the steam generating and gas producing portion of the apparatus and at its end opposite the nozzle curves upwardly towards an outlet or slot 39 formed between two edges extending along the arcs of concentric circles. The portion of the mixing chamber leading up to the outlet 39 also communicates with branches of a distributing chamber 40 extending around the burner tip adjacent to the outlet 39.

Obviously, the chamber 40 might extend completely around the tip of the burner 41 but, as indicated most clearly in Fig. 4, terminates in spaced apart end walls 42 providing a gap through which the water pipe 16 passes to the central part of the burner and the lower end of the boiler. The outlet or slot is of too great width to produce effective burning of the gas or gaseous mixture and would not direct the flames or burning gases to the positions necessary to produce the most effective results. The outlet of the burner is therefore provided with a deflector 42 which preferably consists of a heavy body having a sharp downwardly extending rib 43 projecting into said outlet and is provided both at its sides and ends with ribs or guides 44 which also serve to support the deflector on the walls at the side of the outlet 39. It should also be noted that the ribs 44 and inclined ends of the deflector direct the flame at the end of the deflector

in such manner that substantially a continuous circle of flame is produced. In order to supply air at the center of the burner, the lower wall of the distributing chamber is spaced from the upper wall of the mixing chamber to provide air inlets 40' (Fig. 4). Also, in order to utilize the heat from the burner to advantage, the boiler 10 is provided with a rib or fin 10' projecting outwardly therefrom just above the level of the oil injector 13 and extending around the boiler except at the side above the oil injector. This fin 10' serves to control the currents of hot gases and assures heating of the oil injector, thereby facilitating the vaporization of the oil.

In order to prevent undesirable material in the duct 35 from passing through the gas nozzle 38, provision is made of a suitable strainer or sieve 45 which is here shown as a hollow screen of circular cross section connected at one end with the rear end of the nozzle and at the other end with the open end of a tube 46 with its forward end threaded into an opening 47 in the outer wall 48 of the vertical portion of the duct 35 and in axial alignment with the nozzle 38. The rear end of the said tube or pipe 46 is closed by a cap 49 which may be removed when desired. Attached to the base 32 at the outer side of the wall 48 is an outwardly flared member 50 having at its lower edge a tongue 51 adapted to engage with a groove 52 at the lower side of the floor of the mixing chamber and having at its upper side a perforated inwardly projecting lug 53 adapted to be connected with the wall 48 by means of a screw 54. At its lower side the member 50 is connected with a drain 55 to carry off excess oil when the oil in the mixing chamber has collected until its level is above the higher portion of the floor adjacent to the nozzle 38. Under such conditions, the oil will pass out through the air passages 37 and the drain pipe 55 and may be led, if desired, to a suitable control device.

The flow of air to the inlets 37 may be regulated by a damper 56 including a sleeve 57 slidable along the tube 46 to be secured in suitable position by means of a screw 58. Turning of the damper 56 about the tube 46 may be prevented by guides 59 in the upper part of the member 50 in position to be engaged by the upper edge of the damper at opposite sides of the tube 46. Impurities in the air are kept out of the apparatus by means of a screen 60 extending across the mouth or inlet of the member 50 and secured in position by means including a frame 61.

The base portion 32 of the apparatus may be supported on the floor of the fire box in any suitable manner as, for example, by means of legs 62 (Fig. 2) threaded into bosses 63 projecting downwardly from the

floor of the base 32, thus providing an adjustable three point support.

The apparatus also includes a flash pan 64 of which the floor is on the same level as the main floor 36' of the mixing chamber 36 and which is connected with the mixing chamber by a passage or duct 65 at such floor level. Drainage of both the mixing chamber and the flash pan may be obtained through a passage 66 extending downwardly from passage 65 and communicating with the drain pipe 67 and controlled by a suitable valve 68. The mixing chamber projects into the flash pan so as to leave only a trough to receive oil for burning in starting the apparatus.

The operation of the apparatus is substantially as follows:

When oil is supplied through the pipe 14 in starting the operation of the apparatus, it will collect in the chamber 27 of the oil injector and flow through the Venturi tube 26 into the upper end of the retort 15 and will drain therethrough into the inner end 25 of the duct 35 above the outer end of the mixing chamber. The main portion of the duct 35 slopes downwardly and away from the burner and the oil flows through the duct to the vertical part thereof where it passes 30 through the strainer 45 and is forced through the nozzle 38 towards the center of the apparatus, the oil flowing down the incline between the nozzle 38 and the main floor 36' of the mixing chamber 36 and will collect in the mixing chamber and flash pan 64. If at any time the oil in the mixing chamber rises above the level of the floor adjacent the gas nozzle 38, the surplus oil will flow out through the air passages 37 and down to the 40 drain 55.

The oil in the flash pan is ignited and the heated gases passing upwardly will begin to heat the boiler 10 and the retort 15 and eventually will vaporize the water in the steam chamber 11, thereby causing steam to be supplied to the oil injector 13 and a mixture of steam and atomized or vaporized oil to be supplied to the retort and there combined to form water gas. Ordinarily at the beginning of this operation, water is standing at a predetermined water level determined by suitable means (not shown).

Any water standing in the steam chamber 11 will be evaporated quickly and other water subsequently supplied through the openings in member 17 will be evaporated substantially instantaneously. The gas produced in the retort will then pass through duct 35 and nozzle 38 into the mixing chamber and mixed with air entering through the inlets 37. The mixture will pass up from the forward end of the mixing chamber into the supply or distributing chamber 40 and then upwardly on opposite sides of the deflector 42 and will be guided to a great extent

by the ribs 44. The gaseous mixture will then be ignited at the burner outlet and the apparatus will soon be in full normal operation. The oil in the flash pan 64 will soon be burned out and any oil left therein or in the mixing chamber 36 will be drained therefrom 70 through the tube 67.

The reaction occurring in the retort, the mixing of the products of reaction with air, and the delivery to the burner have been described above. As the temperature rises the water gas reaction becomes complete and the burner having been ignited, the temperature of the flame therein increases and more air is induced through the air inlets until equilibrium is reached for a given rate of fuel supply. When the apparatus is in full normal operation, the oil is completely vaporized and the retort operates at full efficiency, and the gaseous mixture burns with a steady and intense blue flame.

While the size of my device is not an essential feature and while the relative sizes of parts may be varied within limits, it is an important feature that I have succeeded in embodying in a novel and compact arrangement, elements whereby a true and relatively perfect water gas reaction may be brought about. It is an essential of such reaction not merely that the atomized oil be broken down to combustible gas and free carbon, but also there should be the characteristic reaction of water with the free carbon or soot, to form combustible carbon monoxide (CO). My construction of proportional parts is particularly adapted to make certain the proper functioning of the device in this particular. As brought out in said co-pending application, one factor in producing the desired result consists in having the retort tube of great diameter as compared with the capacity of the steam and oil supply device, so that although the steam and oil may enter the coil at a very high velocity and temperature, the cross section of the tube at which they merge will be so large in proportion that the gases will actually travel through the coil quite slowly and be exposed to the heat thereof for the relatively long time necessary to produce the above described result.

Many of the structural details described in the specification are not essential to the success of the invention, for instance, so far as concerns the broader aspects of the invention, the shape of the retort might be varied, other means might be utilized for controlling the flow of water and oil, or for controlling the flow of the gaseous mixture through the outlet of the burner, without departing from the spirit of the invention which may include any and all changes and alterations that fairly fall within the scope of the appended claims.

I claim:

1. A gas producer and burner apparatus 130

adapted for use in a furnace, including a boiler having a steam chamber having very small cross section at the bottom and with walls diverging upwardly at acute angles, 5 means controlling the admission of water to said steam chamber and adapted to admit water at rates causing it to collect in said steam chamber when the apparatus is not in full operation while restricting the flow so that 10 during full normal operation water will be vaporized as fast as admitted to the steam chamber, and a burner adapted to provide an annulus of gases of combustion directed toward the small lower end of the boiler for 15 heating the same so as to cause it to act as a flash boiler.

2. A gas producer and burner apparatus, including a boiler having a steam chamber in the general form of an acute-sided inverted 20 cone, means controlling the admission of water to said steam chamber and adapted to admit water at rates causing it to collect in said steam chamber when the apparatus is not in full operation while restricting the flow so 25 that during full normal operation water will be vaporized as fast as admitted, a gas retort in the form of a coil surrounding said boiler, an injector operated by steam from said boiler to force oil into the upper end of said retort, 30 and a burner adapted to direct an annulus of burning gas against the small lower end of said boiler and to direct an annulus of burning gases upwardly and outwardly beneath the coil of the retort.

35 3. A gas producer and burner apparatus including a boiler having a steam chamber in the general form of an inverted cone and a drying chamber above said steam chamber and separated therefrom by a wall having a 40 central restricted orifice, a gas retort in the form of a coil surrounding said boiler, an oil injector connected with the upper end of said coil relatively close to the boiler and receiving steam centrally from the upper end 45 of said drying chamber and oil around the steam, and a safety valve outlet for the passage between said drying chamber and said injector.

4. In a gas producer and burner apparatus 50 the combination with a burner, of a boiler, a retort in the form of a coil around said boiler, a tubular member projecting laterally from the top of said boiler, an oil injector beneath said tubular member adjacent to said 55 boiler and connected with said tubular member and a source of oil supply and also with the upper end of said coil, and a rib extending around said boiler except at the side at which are positioned the injector and tubular outlet member from the boiler, thereby assuring proper heating of the retort and the boiler.

5. In a gas producer and burner apparatus adapted for use in a furnace, a generally circular burner, a boiler having at its lower end 65

a steam chamber in the form of an acute-sided inverted cone with its lower end adjacent the plane of the burner outlet, means for supplying water upwardly through said burner to the lower end of said steam chamber, and means for restricting the admission of water 70 into said boiler so that while water will collect in said steam chamber when the apparatus is not in full operation, the water will be vaporized during full normal operation as fast as admitted to the steam chamber. 75

6. In a gas producer and burner apparatus having a boiler with a relatively small lower end, a gas retort in the form of a coil around said boiler, an oil injector actuated by steam from the upper part of the boiler and connected with the upper end of the coil to inject a mixture of oil and steam thereinto; a burner having a slot outlet in the form of an arc of an incomplete circle having a gap, 80 a deflector across said opening and having vanes or guides at each side and at the ends thereof to control the flow of air and gas therefrom, the vanes at the end of said deflector serving to direct the gaseous mixtures across the gap to provide a complete circle of combustion. 85

7. In a gas producer and burner apparatus having a boiler with a relatively small lower end, a gas retort in the form of a coil around said boiler, and an oil injector actuated by steam from the upper part of the boiler and connected with the upper end of the coil to inject therein a mixture of oil and steam; a burner having an outlet in the form of an arc of a circle but with a gap therein, said burner being located substantially at the lower end of said boiler, a mixing chamber beneath said burner, and a water supply line above said mixing chamber and extending through said gap to the center of the burner and there communicating with the lower end of the boiler. 95

8. In a gas producer and burner apparatus having a boiler with a relatively small lower end, a gas retort in the form of a coil around said boiler, and an oil injector actuated by steam from the upper part of the boiler and connected with the upper end of the coil to inject a mixture of oil and steam thereinto; a burner having a slot outlet in the form of an arc of an incomplete circle, a deflector across said opening and having a substantial body portion coming to a sharp central edge at the top, a downwardly extending central rib at the bottom, and a plurality of vanes or guides at each side and at the ends thereof to control the flow of air and gas therefrom, the vanes at the end of said deflector serving to direct the gaseous mixture across the gap to provide a complete circle of combustion. 115

9. In a gas producer and burner apparatus having a boiler, a gas retort comprising a coil around said boiler, and an oil injector 120

actuated by steam from the upper end of the boiler and connected with the upper end of the coil to inject a mixture of oil and steam thereinto; a burner having an outlet slot between the circumferences of concentric circles, deflecting means at said outlet slot comprising a heavy body portion with a sharp downwardly projecting rib positioned in said slot and a series of ribs or vanes interposed between each side of said body portion and the corresponding edges of said slot.

10. In a gas producer and burner apparatus having a boiler, a gas retort in the form of a coil around said boiler, and an oil injector actuated by steam from the boiler and connected with the upper end of the coil to inject a mixture of oil and steam into the same; a burner to heat said boiler and coil comprising an outlet having an arcuate slot and a supply or distribution chamber beneath said slot, and a mixing chamber extending beneath said outlet portion and communicating with the middle part of said supply or distribution chamber.

11. In a gas producer and burner apparatus having a boiler, a gas retort in the form of a coil around said boiler, and an oil injector actuated by steam from the boiler and connected with the upper end of the coil to inject a mixture of oil and steam thereinto; a burner to heat said boiler and coil having an outlet in generally circular form and a supply chamber beneath said outlet, a mixing chamber extending beneath the outlet portion of the burner and communicating from below with said supply chamber, and air inlets extending from the outside beneath the supply chamber to supply air upwardly inside of said outlet.

12. In a gas producer and burner apparatus having a boiler, a gas retort in the form of a coil around said boiler, and an oil injector actuated by steam from the boiler and connected with the upper end of the coil to inject a mixture of oil and steam into the same; a burner to heat said boiler and coil comprising an outlet portion including a generally annular distributing chamber, a mixing chamber adapted to receive gas and air at one end and extending beneath said outlet portion to communicate on the opposite side of the burner with the lower side of said distributing chamber, a flash pan bounded by the wall of the mixing chamber at its inner side and at its outer side by a wall concentric with the burner and terminating at the sides of the mixing chamber, and a duct connecting the lower portions of the flash pan and mixing chamber to permit the drainage of oil from either one to the other.

13. In a gas producer and burner apparatus having a boiler, a gas retort in the form of a coil around said boiler, an oil injector actuated by steam from the boiler

and connected with the upper end of the coil to inject a mixture of oil and steam into the same; a burner to heat said boiler and coil comprising an outlet portion including a generally annular distributing chamber, a mixing chamber adapted to receive gas and air at one end and extending beneath said outlet portion to communicate on the opposite side of the burner with the lower side of said distributing chamber, a flash pan bounded by the wall of the mixing chamber at its inner side and at its outer side by a wall concentric with the burner and terminating at the sides of the mixing chamber, a duct connecting the lower portions of the flash pan and mixing chamber to permit the drainage of oil from either one to the other, and a drain duct extending downwardly from the connecting duct intermediate its ends for draining said mixing chamber and flash pan.

14. In a gas producer and burner apparatus having a boiler, a gas retort in the form of a coil around said boiler, an oil injector actuated by steam from the boiler and connected with the upper end of the coil to inject a mixture of oil and steam thereinto; means to heat said boiler and coil comprising a burner outlet portion including a distributing chamber, a mixing chamber extending beneath said outlet portion to communicate on the opposite side of the burner with the lower side of said distributing chamber, a duct connected at its inner end with the lower end of the retort near the boiler and extending along the top of the mixing chamber to the outer end thereof and then downwardly to the floor thereof, and a nozzle communicating with the lower end of said duct and directed into said mixing chamber.

15. In a gas producer and burner apparatus having a boiler, a self-draining gas retort including a coil around said boiler, an oil injector actuated by steam from the boiler and connected with the upper end of the coil to inject a mixture of oil and steam thereinto; means to heat said boiler and coil comprising a burner outlet portion including a distributing chamber, a mixing chamber extending beneath said outlet portion to communicate on the opposite side of the burner with the lower side of said distributing chamber, a duct connected at its inner end with the lower end of the retort near the boiler and extending along the top of the mixing chamber to the outer end thereof and then downwardly to the floor thereof, a nozzle communicating with the lower end of said duct and directed into said mixing chamber, and a screen at the rear end of said nozzle.

Signed at Chicago in the county of Cook, 125 and State of Illinois, this 28th day of April, A. D. 1928.

EDWARD O. BENJAMIN.
